John J. Whitacre,

BY

Harry Grease,

ATTORNEY

UNITED STATES PATENT OFFICE.

JOHN J. WHITACRE, OF CANTON, OHIO.

CONCRETE REINFORCEMENT.

No. 906,479.

Specification of Letters Patent.

Patented Dec. 8, 1908.

Original application filed December 23, 1907, Serial No. 407,733. Divided and this application filed February 21, 1908. Serial No. 416,958.

To all whom it may concern:

Be it known that I, JOHN J. WHITACRE, a citizen of the United States, residing at Canton, in the county of Stark and State of Ohio, have invented a certain new and useful Concrete Reinforcement, the same being illustrated and described, but not claimed, in my application for Letters Patent filed December 23, 1907, Serial No. 407,733, of which application this one is a divisional part, and of which invention the following is a specification.

The invention relates to a metallic reinforcement for a concrete beam wherein a main longitudinal metallic member is employed in or near the lower portion of the beam, to which main member separate subordinate members are connected at intervals apart and are inclined upward in various directions as the tension members of a truss toward the upper portion of the beam; and the object of the invention is to provide a reinforcement which can be conveniently made and put in place as the work progresses and during such making the subordinate members can be located, inclined and arranged with reference to each other, in any desired manner best suited to the respective parts of the beam and the varying requirements of construction. This object is attained by the construction and arrangement illustrated in the accompanying drawings, in which—

Figure 1 is a longitudinal vertical section of a portion of a concrete beam showing a form of the metallic reinforcement therein, having a rectangular main bar set on one side, and in which the diverging wires of each subordinate member are crimped and overlapped with the diverging wires of adjacent members; Fig. 2, a perspective view showing the reinforcement as made with a round main bar, and having the diverging wires of the subordinate members curved to form hooks on their free ends; Fig. 3, a cross section of the same; Fig. 4, a perspective view showing the reinforcement as made with a rectangular main bar placed on edge, and having separate wires for the subordinate members twisted together above and below the main bar and having square hooks bent on the free ends of the diverging wires; and Fig. 5, a cross section of the same.

Similar numerals refer to similar parts throughout the drawings.

The main bar 1 is located longitudinally, to be embedded in the lower portion of the concrete beam 2 when the same is formed around the metallic reinforcement, and this member can be formed square and set on one side as shown in Fig. 1; or it may be round in cross section, as shown at 1^a in Figs. 2 and 3; or it may be formed square and set on edge, as shown at 1^b in Figs. 4 and 5; the particular cross section of the main bar not being an essential feature of the present invention. The subordinate members are each composed of a number of flexible wires, 3, 3^a and 3^b, preferably four in number, which are wrapped around the main member from below upward and brought together to form a single cable in the middle of the upper side, whence they are twisted together upward for a short distance, whence the respective wires are separated and individually inclined diagonally upward through each quadrant of a plane perpendicular to the cable.

A preferred manner of disposing the free ends of the wires is to incline them in slightly diverging directions toward the ends of the beam, and to locate the several subordinate members so that the diverging wires of one member will overlap the diverging wires of an adjacent member, as shown in Fig. 1, by means of which the beam is thoroughly bound together in various directions throughout its body. The diverging wires of the subordinate members may also be crimped, as shown in the same figure, which gives them a better hold in the cement.

In Figs. 2 and 3, the subordinate members are spaced apart so that the diverging wires will not overlap, and the ends are curved to form the hooks 4 which serve to engage in the cement. In Figs. 4 and 5, separate wires are used on opposite sides of the main bar, the same being twisted together below and above the main bar, and the individual wires are separated quite close to the upper side of the main bar, instead of at a point some distance above the same as shown in the other figures. In this figure, the free ends of the diverging wires are bent square to form hooks which engage in the cement.

What I claim as my invention, and desire to secure by Letters Patent, is—

1. A metallic reinforcement for a concrete floor beam comprising a main member, and a series of separate subordinate members lo-

105

110

cated at intervals apart and composed of a plurality of wires wrapped around the main member and twisted together in a single cable on the upper side thereof and thence separated and extended divergently as tension members diagonally upward through each quadrant of a plane perpendicular to the cable.

2. A metallic reinforcement for a concrete floor beam comprising a main member, and a series of separate subordinate members located at intervals apart and composed of a plurality of wires wrapped around the main member and twisted together as a single cable on the upper side thereof and thence separated and extended divergently as tension members diagonally upward through each quadrant of a plane perpendicular to the cable, the individual wires of one subordinate member overlapping the wires of the adjacent subordinate members.

3. A metallic reinforcement for a concrete floor beam comprising a main member, and a series of separate subordinate members lo-

cated at intervals apart and composed of a plurality of wires wrapped around the main member and twisted together in a single cable on the upper side thereof and thence separated and extended divergently as tension members diagonally upward through each quadrant of a plane perpendicular to the cable, the divergent wires being crimped.

4. A metallic reinforcement for a concrete floor beam comprising a main member, and a series of separate subordinate members located at intervals apart and composed of a plurality of wires wrapped around the main member and twisted together in a single cable on the upper side thereof and thence separated and extended divergently as tension members diagonally upward through each quadrant of a plane perpendicular to the cable, the free ends of the wires being bent to engage in the cement.

JOHN J. WHITACRE.
